UNITED STATES PATENT OFFICE.

JOSEPH D. ELDREDGE, OF NEW YORK, N. Y.

SEALING DEVICE.

1,137,592.

Specification of Letters Patent. Patented Apr. 27, 1915.

Application filed September 21, 1914. Serial No. 862,766.

To all whom it may concern:

Be it known that I, JOSEPH D. ELDREDGE, a citizen of the United States, residing at New York, in the county of New York, State of New York, have invented certain new and useful Improvements in Sealing Devices; and I do hereby declare the following to be a full, clear, and exact description of the invention, such as will enable others skilled in the art to which it appertains to make and use the same.

This invention relates to a sealing device.

An object of the invention is to provide a device of this character by means of which doors of freight cars or the like may be locked and effectively sealed.

A further object of the invention is to make provision in the device for the sealing of the lock in such manner that it will be impossible to unlock the same without completely destroying the said seal.

With these and other objects in view, such as will appear as the description progresses my invention comprises the combination and arrangement of parts as set forth in and falling within the scope of the appended claims.

In the drawings: Figure 1 is a front elevation of my device showing the same in locked position; Fig. 2 is a plan view thereof; Fig. 3 is a section on the line 3—3 of Fig. 1, and Fig. 4, is a section on the line 4—4 of Fig. 2.

Referring to the drawings by reference characters wherein like parts are indicated by like characters throughout the several views: my device comprises a plate 1 having an outwardly projecting lug 2 thereon to which is formed an opening 3. This member 1 is arranged to be secured to the jamb of a door. Detachably secured to this lug 2 is a hasp 4 which has a hinged portion 5 thereon on the said portion having knuckles 6 thereon which register with a knuckle 7 on the said hasp 4. Passing through these registering ears is a pin which is countersunk in the ears 6 and prevented from longitudinal displacement by outwardly extending flanges 9 on the said member 5, the latter ears bearing 50 against the ends of the said pin. A plate 10 is provided and is arranged to be secured to the jamb in spaced relation to the said plate 1. Pivotedly mounted on this plate 1 is a hook 11 which has a downwardly extending curved bill 12 the said bill being of the same configuration in cross section as the hole

through the lug 2. In the lower ends of this bill 12 is a transversely extending rectangular hole 13 which terminates in openings in the face of the bill. Extending at right angles to this hole 13 is a cylindrical hole 14 which intersects the said hole 13 midway between the ends thereof. In order that this bill 12 may be sealed within the lug 2 I have provided a rectangular pin 15 made of lead or some other soft metal which I place through the hole 13 after the bill has been inserted through the hole in the lug 2 so that the ends of the said pin 15 project from the openings in the face of the said bill. A suitable tool is then placed in the hole 14 to one side of the said pin 15 and force is applied thereto so that the metal at this point in the pin 15 is pressed from both sides of the hole 14 and is spread to fill the counter bore which is grooved in the center of the hole 14. The ends of the said pin 15 are then upset so as to doubly prevent the extracting of the said pin without so mutilating it as to be noticeable.

When it is desirable to unseal the device the upset portion on both sides of the pin is cut-away by a conveniently sharp instrument such as a knife or the like, the pin is then pulled from the other side of the bill 12, shearing the portion of the metal in the hole 14, therefrom. The portion of the pin thus remaining in the hole 14 may be readily punched therefrom and the bill 12 withdrawn from the lug 2 so that the hasp 4 may be disengaged from the said lug and the door conveniently opened.

From the foregoing description it may be readily seen that I have provided a sealing device by means of which locks may be so sealed that they may not be opened without destroying said seal.

While I have illustrated my device in connection with a particular kind of lock I wish it to be understood that different types may be used, for instance those used in connection with sliding doors, and I therefore do not wish to be limited to the particular construction illustrated as it is obvious that numerous other changes may be made in the details of construction without departing from the spirit of the invention and without exceeding the scope of the claims.

What is claimed is:

1. A device for securing a hasp to a keeper including a pin arranged to extend through said keeper, the said pin having transversely

extending holes arranged at right angles to each other and a pin mounted in one of said holes and having a portion thereof extending into the other of said holes.

5. 2. A device for securing a hasp to a keeper including a pin arranged to extend through said keeper, and having transversely extending holes therein arranged at right angles to each other, one of said holes having enlargements between its ends and a metallic strip 10 extending through said last mentioned hole

and having a portion extending into the other of said transversely extending holes and portions extending into said enlargements.

In testimony whereof, I affix my signature, in the presence of two witnesses.

JOSEPH D. ELDRIDGE.
